(57) CLAIM

The ornamental design for a slime-shaped helmet, as shown and described.

DESCRIPTION

FIG. 1 is a front perspective view of my slime-shaped helmet;

FIG. 2 is a front view thereof;

FIG. 3 is a rear view thereof;

FIG. 4 is a right-side view thereof;

FIG. 5 is a left-side view thereof; and

FIG. 6 is a top view thereof; and,

FIG. 7 bottom view thereof.

The broken lines illustrate environmental features and form no part of the claimed design.
